UNITED STATES PATENT OFFICE

135,712

DESIGN FOR AN APRON

Muriel King, Pleasantville, N. Y., assignor to Celanese Corporation of America, a corporation of Delaware

Application March 30, 1943, Serial No. 109,868

Term of patent 7 years

To all whom it may concern:

Be it known that I, Muriel King, a citizen of the United States, residing at Pleasantville, in the county of Westchester and State of New York, have invented a new, original, and ornamental Design for an Apron, of which the following is a specification, reference being had to the accompanying drawing, forming part thereof.

In the accompanying drawing:

I claim:

The ornamental design for an apron, as shown.

MURIEL KING.
